UNITED STATES PATENT OFFICE.

FRANK J. SHIVELY, OF CANTON, OHIO.

DOOR-IRON.

1,373,774.

Specification of Letters Patent.

Patented Apr. 5, 1921.

Application filed March 6, 1920. Serial No. 363,654.

To all whom it may concern:

Be it known that I, FRANK J. SHIVELY, a citizen of the United States, residing at Canton, in the county of Stark and State 5 of Ohio, have invented a new and useful Door-Iron, of which the following is a specification.

This invention relates to door irons and more particularly to a door iron designed 10 for use upon automobiles and has for its objects the provision of such a device arranged to connect an automobile door with the side curtain therefor and adapted to hold the side curtain taut in both the open and closed positions of the door and to generally improve 15 and simplify devices of this character and produce an inexpensive and efficient door iron.

With these objects in view the invention 20 consists in the novel construction and arrangement of parts, hereinafter described, illustrated in the accompanying drawings, and particularly pointed out in the appended claims, it being understood that various 25 changes in the form, proportions, size and minor details of construction may be made within the scope of the appended claims, without departing from the spirit or sacrificing any of the advantages of the invention.

The invention thus set forth in general terms is illustrated in the accompanying drawings forming part hereof, in which—

Figure 1 is an interior view of a portion 25 of an automobile door and side curtain therefor showing my improved door iron applied thereto, the door being shown in the closed position.

Fig. 2 is a similar view showing the door 40 in the opened position.

Fig. 3 is a front elevation of the door iron upon an enlarged scale; and

Fig. 4 is an edge elevation of the same.

A practical embodiment of the invention 45 is disclosed in the accompanying drawings, forming a part of this specification in which similar numerals of reference indicate corresponding parts throughout the several views.

50 Referring to Figs. 1 and 2, a portion of a hood of an automobile is shown at 1, the front door at 2 being hinged thereto at 3 and a wind shield 4 being mounted thereon, all of these parts being of the usual construction.

A side curtain 5 is connected to the wind shield along its forward edge and at its rear edge is provided with a tunnel 6 within which is mounted a strip 7 preferably of wood which holds the rear edge of the side 60 curtain rigid.

A keeper 8 is connected to the door preferably upon the inner side thereof at a point near the swinging edge, said keeper being preferably provided with ears 9 through 65 which screws or other fastening means are located.

The bolt 10 is normally located in the keeper 8 and is provided at its upper end with the enlarged head 11, the arm 12 which 70 is also provided with a similar head 13 being pivotally connected thereto by means of a rivet 14 or the like. The arm 12 is provided with the lug 15 and a similar lug 16 is provided upon the bolt 10, a coil spring 75 17 connecting said lugs.

A bar 18 is pivotally connected at 19 to the strip 7 and the lower end of said bar is bent at right angles as shown at 20 and passed through the socket 21 in the arm 12, 80 a set screw 22 or the like being provided for rigidly holding the end of the bar within said socket.

When the door iron is applied to the door and side curtain as shown in Figs. 1 and 2 85 the tension upon the spring 17 will hold the curtain taut at all times. Where a wind shield is inclined at an angle to the perpendicular as illustrated in the drawings the top edge of the curtain is necessarily shorter 90 than the bottom edge thereof and when the door is opened as shown in Fig. 2 the top edge of the curtain will be held taut, the bar 18 being rocked upon its pivotal points 14 and 19 into substantially the position shown in 95 said figure, slight fullness being produced in the lower edge of the curtain. As the door is closed the spring 17 will draw the bar 18 back into the normal position bringing the curtain into the position shown in 100 Fig. 1.

Although the drawings and above specifications disclose the best mode in which I have contemplated embodying my invention I desire to be not limited to the details of 105 such disclosure, for, in the further practical application of my invention, many changes in form and construction may be made, as circumstances require or experience suggests, without departing from the spirit 110.

of the invention, within the scope of the appended claims.

I claim:—

1. A door iron comprising a keeper adapted to be connected to a vehicle door, a bolt adapted to be normally seated in said keeper, an arm pivotally connected to said bolt and arranged to be pivotally connected to the edge of a door curtain and a spring connecting said bolt and said arm to hold the curtain taut. 10

2. A door iron comprising a keeper adapted to be connected to a vehicle door, a bolt adapted to be normally seated in said keeper, an arm pivotally connected to said bolt, a bar rigidly connected to said arm and adapted to be pivotally connected to the 15

edge of a door curtain and a spring connecting said bolt and said arm to hold the curtain taut. 20

3. In combination with a vehicle door and a door curtain provided with a stiffening strip at its swinging edge, a door iron comprising a keeper connected to the swinging edge of the door, a bolt adapted to be normally seated in said keeper, an arm pivotally mounted on said bolt, lugs upon said arms and bolt, a spring connected to said lugs and a bar rigidly connected to said arm and pivotally connected to said stiffening strip. 25 30

In testimony that I claim the above, I have hereunto subscribed my name.

FRANK J. SHIVELY.
